UNITED STATES PATENT OFFICE.

AARON MOREHOUSE, OF DANBURY, CONN., ASSIGNOR TO THE HAT SWEAT MANUFACTURING COMPANY, OF PHILADELPHIA, PENNSYLVANIA.

METHOD OF SEWING.

SPECIFICATION forming part of Letters Patent No. 356,415, dated January 18, 1887.

Application filed June 23, 1886. Serial No. 205,079. (No model.)

To all whom it may concern:

Be it known that I, AARON MOREHOUSE, a citizen of the United States, residing at Danbury, in the county of Fairfield and State of Connecticut, have invented a certain new and Improved Method of Sewing, of which the following is a full, clear, and exact specification, reference being had to the accompanying drawings, forming a part thereof.

10 My invention consists in an improved method of sewing, in which the result aimed at is to produce a seam showing upon one side of the fabric or material as a row of loops in substantially the same line, but meeting a row of 15 other loops parallel to each other at an angle, and upon the other side of the fabric or material as two parallel rows of stitches closely drawn into the fabric, and in every way resembling two lines of ordinary sewing-machine 20 stitching.

I am aware that double seams showing upon one side whip or diagonal stitches are old; but I have invented a new and improved method of producing such a seam, requiring the use of 25 but two instead of three threads, and making a very elastic stitch.

In order to form my stitch I preferably make use of a machine for which I have made application for Letters Patent of the United 30 States, the said application having been filed on or about June 18, 1886, and serially numbered 205,538, in which I make use of two eye-pointed needles of unequal length (and by 35 unequal length I mean needles which descend to unequal distances below the cloth) vertically reciprocating in a plane cutting the line of feed at right angles, or nearly so, each provided with threads, as usual, and beneath the cloth-plate a vibratory looping-hook of peculiar construction.

I do not give further details of the construction of the machine, for these are fully set forth in the said application above referred to, filed coincident herewith, and for the reason that 45 this patent is for the method of sewing, and not for any special machinery whereby the threads may be concatenated.

The general nature of this improved method of sewing may be set forth as follows: The two 50 needles descending penetrate the material which is to be sewed and form loops on their

ascent upon the under side. These loops are caught by a vibratory looper and drawn out and held. On their next descent one of the needles penetrates both loops, which are drawn up against the under side of the fabric or material, forming a chain-stitch, having inter-looped therewith a series of loops whose sides are closely drawn together, and which meet the said chain at an oblique angle.

Figure 1 of the drawings is a perspective sketch of the seam produced by this improved method supposed to be removed from the fabric or material upon which it is made. Fig. 2 is a plan view of the upper surface of a piece 65 of material stitched in accordance with my improved method. Fig. 3 is a plan view of the under surface of the same seam, showing the peculiarities of the stitch. Figs. 4 to 12, inclusive, are diagrams representing the relative positions of the needles and the looping-hook, showing the different phases of the formation of the stitch. These diagrams will be explained severally in the description of the details of the method of sewing herein set 70 forth.

A is the thread which forms the ordinary chain-stitch. B is the thread which forms the diagonal stitch. The parts of the thread marked *a* and *b* are upon the upper side of the 80 fabric. The remaining parts of both threads are either upon the under side or within the substance of the fabric. H is the vibratory looping-hook; R, the material being sewed; *f*, the shorter needle; *f'*, the longer one; *h*, loop-spreader, forming a part of the looping-hook H.

The ordinary arrows on the drawings indicate the direction of the motion of the needles and the looping-hook at different stages of the process. A double-headed arrow indicates a 90 period of rest.

To explain more in detail the formation of the stitch, I will describe the diagrams 4 to 12, inclusive. In Fig. 4 the needles are shown above the cloth-plate, ready to penetrate the 95 fabric for the first stitch. The hook is at rest at its farthest backward point. In the position shown in Fig. 5 the needles have penetrated the fabric and descended to their lowest position and are rising to form loops, as 100 usual, which loops are being entered by the point of the looping-hook moving forward. In

Fig. 6 the needles, having reached their highest point, have commenced to descend, and are again ready to penetrate the fabric, the feed has carried the fabric forward the length of one stitch, and the hook, holding both loops, is at its period of rest preparatory to its return-stroke. In Fig. 7 the needles are shown moving farther downward, the shorter one just entering both the loops, held open for the passage of the needle by the loop opener or spreader h' , and the hook has started on its backward trip. In Fig. 8 the short needle is shown completely through both loops, and the hook, retreating still farther, is about to leave both loops surrounding the shorter needle, f . In Fig. 9 the needles are shown as having again reached their lowest point and just commencing to rise, with both loops slipped from the hook and drawn up around the short needle, and with the hook again on its forward stroke, new loops forming by the ascent of the needles and ready for the hook to enter them, as shown in the next figure. The loop on the shorter needle, f , is forming below and with its neck inclosed in the two other loops, which are nearly drawn up around the said needle. In Fig. 10 the needles have ascended a little higher, having completed a second pair of loops (which the hook is about entering) in the same manner as that which is shown in Fig. 5. In Fig. 11 the hook is still moving forward through the second set of loops, the needles are still rising, the shorter needle just rising out of the first set of loops in the under side of the fabric, where they are held in place by the second loop from the shorter needle, f , which is drawn through both of them, and held on the hook, together with the second loop from the longer needle, f' . In Fig. 12 the needles, after having risen to their highest point, are shown as having again descended to their lowest point, having passed in their descent through both of the second

set of loops and the hook is leaving them similar to Fig. 8, the fabric has in the meantime, under the influence of the feed, moved forward the space necessary for another stitch. 45

The operation continues, as above described, completing the seam. 50

The advantages of this method of sewing are that but two threads are used, which are both needle-threads, and the resulting seam is very elastic, which is a valuable feature in the manufacture of hat-sweats, and for many other purposes. 55

Having now fully described my invention, what I claim, and desire to secure by Letters Patent, is—

The herein-described method of forming a seam or concatenating two threads in connection with cloth, leather, &c., which consists, essentially, first, in passing two loops of thread from the upper to the under side of the cloth, the line passing through said loops being at right angles to the completed seaming; second, in seizing and holding said loops beneath the cloth in such position that when a second set of loops is passed down through the cloth one of said second set of loops shall pass through both of the first set of loops which are held below the cloth; third, in passing a second set of loops through the cloth, one of said second set being made to pass through both of the first set of loops, and, fourth, in seizing and holding said second set of loops below the cloth in such position that one of a third set of loops shall pass through both loops of the second set, and so on in succession, to form a seam of any desired length, substantially as described. 60 65 70 75

In witness whereof I have hereunto set my hand. 80

AARON MOREHOUSE.
